Fig. 2.

Fig. 3.

Fig. 4.

Fig. 1.

FIG. 1 is a front elevational view of a handbag lock showing my new design in closed position;

FIG. 2 is an exploded perspective view showing the turn lock member in open position;

FIG. 3 is a top end view thereof; and

FIG. 4 is a side elevational view thereof.

The rear elevational view is the same as the front elevational view in configuration except that the cross turn lock is omitted and the surface is plain and unornamented.

I claim:

The ornamental design for a handbag lock, substantially as shown and described.
